DESIGN FOR A KNIFE OR SIMILAR ARTICLE

Fred D. Patti, Chicago, Ill.

Application July 6, 1946, Serial No. 131,336

Term of patent 7 years

(CL. D22—3)

To all whom it may concern:

Be it known that I, Fred D. Patti, a citizen of the United States and a resident of Chicago, in the county of Cook and State of Illinois, have invented a new, original, and ornamental Design for a Knife or Similar Article, of which the following is a specification, reference being had to the accompanying drawing, forming a part thereof.

Fig. 1 is an edge elevational view of a knife or similar article showing my new design.

Fig. 2 is a side elevational view of the same, but on double scale, taken as indicated by the line 2—2 in Fig. 1, the opposite side presenting substantially the same appearance as the side shown.

Fig. 3 is an enlarged sectional view taken as indicated by the line 3—3 in Fig. 2.

The essential features of my design are disclosed in full lines.

I claim:

The ornamental design for a knife or similar article, substantially as shown and described.

FRED D. PATTI.
